UNITED STATES PATENT OFFICE.

HARRY BAKER, OF LEBANON, PENNSYLVANIA.

RAIL-JOINT.

1,174,468.

Specification of Letters Patent.

Patented Mar. 7, 1916.

Application filed January 8, 1916. Serial No. 71,009.

To all whom it may concern:

Be it known that I, HARRY BAKER, a citizen of the United States, residing at Lebanon, in the county of Lebanon and State 5 of Pennsylvania, have invented a new and useful Rail-Joint, of which the following is a specification.

This invention relates to rail joints, one of its objects being to provide rails having 10 their ends so shaped as to provide tongues, the tongues on one rail being adapted to lap the webs of the next adjoining rails and to be secured thereto in any manner desired, air spaces being provided between the ends 15 of the rails and between the tongues and the webs of the rails so that air is free to circulate between the parts, thus to prevent injury due to frost which might accumulate between the rails.

20 With the foregoing and other objects in view which will appear as the description proceeds, the invention resides in the combination and arrangement of parts and the details of construction hereinafter described 25 and claimed, it being understood that changes in the precise embodiment of the invention herein disclosed, can be made within the scope of what is claimed, without departing from the spirit of the invention.

30 In the accompanying drawings the preferred form of the invention has been shown.

In said drawings:—Figure 1 is a side elevation of a rail joint embodying the present improvements. Fig. 2 is a section on line A—B Fig. 1. Fig. 3 is a section on line C—D Fig. 2. Fig. 4 is a perspective view of one end of a rail embodying the present improvements.

40 Referring to the figures by characters of reference 1 designates base flanges of a rail and this rail includes the usual web 2 and head or ball 3. In the drawings, only one end of each rail has been illustrated but it 45 is to be understood that both ends of a rail are the same. Each end is thickened as at 4 and has a tongue 5 extending therefrom, this tongue being formed with a base flange extension 6 and with a supporting flange 7.

50 The supporting flange is adapted to fit close against the bottom of the head of the adjoining rail, while the base flange extension 6 is adapted to rest upon one of the base

flanges of the adjoining rail. Formed along the inner side of the tongue 5 is a channel 55 8 and the end of the web of the rail is cut away diagonally, as at 9 so as to provide a diagonal channel. As all of the rails used are to be duplicates, it will be apparent that by placing each rail opposite each of the 60 adjoining rails, the webs of the two rails can be brought together as shown in Fig. 2 and the tongue at each end of each rail will engage and lap the side of the web of the 65 next adjoining rail. Furthermore the diagonal channels or recesses 9 in the meeting ends of the webs will register so as to form a connecting passage through which air is free to circulate from the channel 8 in one tongue to the channel 8 in the other tongue 70 at the joint.

The rails can be fastened together in any manner desired. For example, a bolt 10 can be extended transversely through each tongue 5 and the adjacent web 2 and in addition thereto a latch 11 may be pivotally connected to each web by means of a rivet 12 or in any other suitable manner, this cam being adapted to lap the tongue 5 of the adjoining rail so as to hold said tongue 80 tight against the web to which the latch is secured. An additional fastening means comprises a spike 13 extending downwardly through registering openings 14 in one of the base flanges 1 and in the base flange extension 6. While in the drawings the joint has been shown provided with all three forms of fastening means, it is to be understood that any two of these means can be 85 used or, if preferred, any one of them can 90 be used. In any event an efficient connection will be set up between the parts.

What is claimed is:—

A rail joint including abutting like rails, each including a web, base flanges, a head, 95 each end of the web being thickened, tongues extending from the thickened ends of the webs and having longitudinal grooves in their inner faces in communication with diagonal grooves in the ends of the webs, 100 each tongue having a base flange extension adapted to lap the base flange of the adjoining rail, there being registering openings within said extension and the lapped portion of the base of the rail, said openings 105 being adapted to receive a spike, and means

for fastening each tongue to the web of the rail lapped thereby, said fastening means including a latch pivotally connected to the web of one rail and adapted to swing into lapped relation with the tongue on the opposed rail.

In testimony that I claim the foregoing as

my own, I have hereto affixed my signature in the presence of two witnesses.

HARRY BAKER.
